STORAGE CABINET

Frank Joseph Stiene, Ridgewood, N.J., assignor to Mercedes-Benz of North America, Inc., Montvale, N.J.

Filed Aug. 21, 1972, Ser. No. 282,575

Term of patent 14 years

Int. Cl. D6—04

U.S. Cl. D6—150

FIG.1

FIG.6

FIG. 1 is an oblique perspective view from in front and above, of a storage cabinet embodying my novel design;

FIG. 2 is a front view of the storage cabinet of FIG. 1;

FIG. 3 is a rear view of the storage cabinet of FIG. 1;

FIG. 4 is a side view of the storage cabinet of FIG. 1;

FIG. 5 is a top view of the storage cabinet of FIG. 1; and

FIG. 6 is a rear view of the storage cabinet of FIG. 1.

I claim:

The ornamental design for a storage cabinet, as shown and described.
